UNITED STATES PATENT OFFICE.

ALFORD LEWIS MONTAGUE, OF DUNKIRK, NEW YORK.

WASHING-MACHINE.

SPECIFICATION forming part of Letters Patent No. 361,311, dated April 19, 1867.

Application filed December 10, 1886. Serial No. 221,170. (No model.)

To all whom it may concern:

Be it known that I, ALFORD LEWIS MONTAGUE, a citizen of the United States, residing at Dunkirk, in the county of Chautauqua and State of New York, have invented certain new and useful Improvements in Washing-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The invention will first be described in connection with the drawings, and then pointed out in the claim.

Figure 1 of the drawings is a perspective view of my improved washing-machine; Fig. 2, a cross-section on line $x-x$ of Fig. 1, and Fig. 3 a longitudinal section on line $y-y$ of Fig. 1.

In the drawings, A represents the clothes-box, which is arc-shaped and middle-pivoted at a on the frame B. The box is preferably provided with two hinged covers, a' , secured, when closed, by suitable spring-catches, a^2 .

C C represent two air-pipes—one at each end.

On the inside of the box is arranged the movable or traveling beater D, which is in the form of an isosceles triangle and provided with roller d at the top.

E E are slats in the ends of the box A; and F represents the course of the water as the box is rocked back and forth.

The operation is as follows: The usual supply of hot water and soap-suds being poured into the box, the clothes are arranged on both sides of the beater D and the hinged covers latched down. The clothes, being saturated with soap and water, are squeezed and pounded by the beater as the box moves up and down upon opposite sides. As the clothes move from one side the vacuum thus created is filled by air rushing in through the pipe on that side, while this air, which permeates the clothes and becomes loaded with impurities, is expelled on the return movement of the beater and box. By this means the yellowing of clothes, to which so much exception is taken, may be entirely prevented.

Having thus described my invention, what I claim as new, and desire to protect by Letters Patent, is—

In a washing-machine, the arc-shaped box A, pivoted at its middle on a frame, B, having an air-pipe, a^2 , at each end, and provided with the inside end slats, E E, in combination with a triangular traveling beater, D, having one roll to bear upon the top of box and two to bear upon the bottom, substantially as shown and described.

In testimony whereof I affix my signature in presence of two witnesses.

ALFORD LEWIS MONTAGUE.

Witnesses:

JOSEPH HOELLIG,
ALBERT WICHMAN.
